US0D1064266S

(12) **United States Design Patent** (10) **Patent No.:** **US D1,064,266 S**
(45) **Date of Patent:** **** Feb. 25, 2025**

(54) **HANDLE FOR A MEDICAL INSTRUMENT**

(71) Applicant: **Auris Health, Inc.**, Redwood City, CA (US)

(72) Inventors: **Akira Bryan Ueda**, San Francisco, CA (US); **Melissa A. Teran**, Redwood City, CA (US); **Aadel Al-Jadda**, San Carlos, CA (US); **Andre J. Castillo**, Redwood City, CA (US); **Francois Pierre René Dransart**, San Francisco, CA (US); **Jaeyeon Kwon**, San Francisco, CA (US)

(73) Assignee: **Auris Health, Inc.**, Redwood City, CA (US)

(**) Term: **15 Years**

(21) Appl. No.: **29/944,121**

(22) Filed: **May 25, 2024**

Related U.S. Application Data

(63) Continuation of application No. 29/915,946, filed on Nov. 6, 2023, now Pat. No. Des. 1,029,251, which is a continuation of application No. 29/861,055, filed on Nov. 25, 2022, now Pat. No. Des. 1,006,224, which is a continuation of application No. 29/701,981, filed on Aug. 15, 2019, now Pat. No. Des. 975,275.

CLAIM

The ornamental design for a handle for a medical instrument as shown and described.

DESCRIPTION

FIG. 1 is a top, front, right perspective view of a handle for a medical instrument;

FIG. 2 is a bottom, rear, left perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines illustrate portions of the handle for a medical instrument and form no part of the claimed subject matter.

1 Claim, 7 Drawing Sheets
